UNITED STATES PATENT OFFICE

152,155

DESIGN FOR A SCREW DRIVER

Sydney Jacoff, Kew Gardens, N. Y.

Application August 14, 1947, Serial No. 140,862

Term of patent 14 years

(Cl. D93—4)

To all whom it may concern:

Be it known that I, Sydney Jacoff, a citizen of the United States, residing at Kew Gardens, county of Queens, State of New York, have invented a new, original, and ornamental Design for Screw Driver, of which the following is a specification, reference being had to the accompanying drawing, forming a part thereof, in which:

Fig. 1 is a front elevation of a screw driver, showing my new design;

Fig. 2 is a side elevation of the same, the shank, in broken lines, being shown fragmentarily for convenience and illustration; and

Fig. 3 is a top plan view of the same.

I claim:

The ornamental design for a screw driver, as shown and described.

SYDNEY JACOFF.
